ATTORNEY

UNITED STATES PATENT OFFICE.

JOHN H. HARMSTONE, OF ATTLEBORO, MASSACHUSETTS, ASSIGNOR TO R. BLACKINTON & CO.,
OF NORTH ATTLEBORO, MASSACHUSETTS.

DESIGN FOR A HANDLE FOR SPOONS, FORKS, OR SIMILAR ARTICLES.

No. 39,834.

Specification for Design.

Patented Feb. 23, 1909.

Application filed January 15, 1909. Serial No. 472,556. Term of patent 7 years.

To all whom it may concern:

Be it known that I, JOHN H. HARMSTONE, a citizen of the United States, and residing at Attleboro, in the county of Bristol and State of Massachusetts, have invented a new, original, and ornamental Design for the Handle of a Spoon, Fork, or Similar Article, reference being had to the accompanying drawing.

The drawing represents a view of the

obverse side of the handle, showing my design, the tines of a fork being indicated in broken lines.

I claim—

The ornamental design for the handle of a spoon, fork or similar article, as shown.

JOHN H. HARMSTONE.
